UNITED STATES PATENT OFFICE.

DAVID STOLL, OF NEW YORK, N. Y.

DESIGN FOR A PITCHER OR SIMILAR ARTICLE.

Application filed March 14, 1923. Serial No. 5,471. Term of patent 3½ years.

To all whom it may concern:

Be it known that I, DAVID STOLL, a citizen of the United States, and resident of the city of New York, in the county of Kings and State of New York, have invented a new, original, and ornamental Design for a Pitcher or Similar Article, of which the following is a specification, reference being had to the accompanying drawing, forming part thereof.

The figure is a perspective view of a pitcher to which my new design has been applied.

I claim:

The ornamental design for a pitcher or similar article, as shown.

Signed at the city of New York, in the county of New York and State of New York, this 13th day of March, 1923.

DAVID STOLL.
